UNITED STATES PATENT OFFICE.

RALPH S. PEIRCE, OF HINSDALE, ILLINOIS.

ANCHORING DEVICE.

Application filed December 10, 1923. Serial No. 679,807.

To all whom it may concern:

Be it known that I, RALPH S. PEIRCE, citizen of the United States, residing at Hinsdale, in the county of Du Page and 5 State of Illinois, have invented a certain new and useful Improvement in Anchoring Devices, of which the following is a full, clear, concise, and exact description.

My invention relates to anchoring devices 10 of the class employing expanding elements and elements of softer material expansible thereby. The invention has for its general object the provision of a second expanding element which operates as a tool in conjunction 15 with the first for expanding the expandable element and which has an improved assemblage with either and preferably both of the other elements whereby it is constantly in position to be used as a tool for 20 this intended purpose.

In accordance with one characteristic of the invention, the second expanding element or tool is initially and permanently assembled with the expansible element. In accordance 25 with another characteristic of the invention, the second expanding element or tool and the first expanding element are provided with interengaging formations which positively effect the initial assemblage 30 of the two expanding elements without relying upon friction for this purpose.

In the preferred embodiment of the invention the second expanding element or tool is assembled with both of the other elements of the anchoring device in a manner 35 to maintain all of them together as a unit ready for installation when desired.

The invention will be more fully explained with reference to the accompanying 40 drawing showing the preferred embodiment thereof and in which Fig. 1 is an axial sectional view illustrating the anchoring device inserted in place and in readiness to be adjusted by the expanding tool element thereof; Fig. 2 is a view similar to Fig. 1 but showing the anchoring device adjusted in a holding position and illustrating an object held thereby; Fig. 3 is a view similar to Fig. 2 with the exception that the expanding 45 tool element of the device is shown in elevation; Fig. 4 is a view illustrating the parts having the relation shown in Fig. 1, the two expanding elements being shown in elevation and the expansible elements being 50 shown in section; and Fig. 5 is a sectional view on line 5—5 of Fig. 3.

Like parts are indicated by similar characters of reference throughout the different figures.

The expanding element 1 is shown in the 60 form of a tapering or conical nut which is to be held in position within a wall or other support to receive a bolt 3 employed for any purpose, such as, the mounting of a clothes hook 4. The expansible element 5 is employed 65 for maintaining fixed assemblage of the nut 1 and the support 2. This expansible element is desirably formed with a bore tapering similarly to the nut 1 which is received in this bore. These two elements 70 are maintained in permanent assemblage, prior to use, by means of an internal rib 6 formed upon and within the expansible element 5 and entering the annular groove 7 in the nut. The expansible element is desirably 75 formed of lead and the annular rib 6 is produced by advancing the expansible element under pressure and squeezing it to cause the metal to flow into the groove. The expanding tool 8 which is employed in cooperation 80 with the expanding element 1 to expand the expansible element 5 is caused to be a component part of the anchoring device by being assembled with either, and preferably both, of its complemental elements. 85

In the preferred embodiment of the invention the expanding tool is in the form of a flanged hollow cylinder 8 that has a series of longitudinal slots 9 formed along and 90 through the same. This cylinder is preferably roughened at its inner end as indicated at 10 to have holding engagement with the outer end of the expansible element 5 that is placed thereover. The assembly 95 of the expanding tool 8 with the balance of the anchoring device is desirably further assured by providing a positive initial interengagement of the two expanding elements without depending upon friction. This interengagement is desirably effected 100 by providing lugs 11 upon the inner sides of the fingers formed out of the cylinder 8 by the slots 9 and by forming another annular groove 12 in the nut 1 which receives these lugs that are sprung into the same when the cylinder is moved sufficiently inward to bring the lugs into the zone of this groove. 105

The expansible element 5 desirably extends to the rear end of the expanding element 1, the expanding tool 8 being forced 110

- 2 by means of hammer blows upon its flange 8', or otherwise, further between the expanding element 1 and the expansible element 5 to spread the latter laterally to have 5 the desired gripping engagement with the support 2. In the final portion of the inward movement of the expanding element 8 its flange 8' compresses the expansible element 5 in an axial direction to cause further lateral 10 spreading movement thereof and to prevent its exudance forwardly. It will be seen that the expanding element 1 performs its function through the intermediation of and in cooperation with the expanding element 8, 15 which itself is expanded by the expanding element 1. To prevent the expanding element 1 from turning with respect to the parts surrounding it, I form it with roughened portions 13 which grip the inner end 20 of the expanding element 8. The roughened portions 10 upon the expanding element 8 engage the inner end of the expansible element 5 further to guard against the turning of any of the elements of the anchoring device with respect to the support 2 receiving the same.
- It is obvious that changes may be made without departing from the spirit of my invention.
- 30 Having thus described my invention I claim as new and desire to secure by Letters Patent the following:—
1. An anchoring device including an expanding element; an expansible element soft relatively to the expanding element that is adapted to be within and is in expanding relation to the expansible element; and a second expanding element initially, permanently and directly assembled with 35 said expansible element and in expanding relation thereto.
2. An anchoring device including a tapered expanding element; an expansible element soft relatively to the expanding element that is adapted to be within and is in expanding relation to the expansible element; and a second expanding element initially, permanently and directly assembled with said expansible element and in expanding 40 relation thereto.
3. An anchoring device including an expanding element; an expansible element soft relatively to the expanding element that is adapted to be within and is in expanding relation to the expansible element and initially and permanently assembled therewith; and a second expanding element initially, permanently and directly assembled with said expansible element and in 45 expanding relation thereto.
4. An anchoring device including a tapered expanding element; an expansible element soft relatively to the expanding element that is adapted to be within and is in expanding relation to the expansible element and initially, permanently and directly assembled with said expansible element and in expanding 50 relation thereto.

ment and initially and permanently assembled therewith; and a second expanding element initially, permanently and directly assembled with said expansible element and in expanding relation thereto.

70

5. An anchoring device including a tapered expanding element; an expansible element soft relatively to the expanding element that is adapted to be within and is in expanding relation to the expansible element; and a second expanding element initially, permanently and directly assembled with one of the aforesaid elements and in expanding relation to the expansible element.

75

6. An anchoring device including an expanding element; an expansible element soft relatively to the expanding element that is adapted to be within and is in expanding relation to the expansible element and initially and permanently assembled therewith; and a second expanding element initially, permanently and directly assembled with one of the aforesaid elements and in expanding relation to the expansible element.

80

7. An anchoring device including a tapered expanding element; an expansible element soft relatively to the expanding element that is adapted to be within and is in expanding relation to the expansible element and initially and permanently assembled therewith; and a second expanding element initially, permanently and directly assembled with one of the aforesaid elements and in expanding relation to the expansible element.

85

8. An anchoring device including an expanding element; an expansible element soft relatively to the expanding element that is adapted to be within and is in expanding relation to the expansible element; and a second expanding element initially, permanently and directly assembled with said expansible element and in expanding relation thereto, the second expanding element being interposed between the aforesaid elements and expansible by the first expanding element and cooperating therewith to expand the expansible element.

90

9. An anchoring device including an expanding element; an expansible element soft relatively to the expanding element that is adapted to be within and is in expanding relation to the expansible element and initially and permanently assembled therewith; and a second expanding element initially, permanently and directly assembled with said expansible element and in expanding relation thereto, the second expanding element being interposed between the aforesaid elements and expansible by the first expanding element and cooperating therewith to expand the expansible element.

100

10. An anchoring device including an ex-

115

- panding element; an expansible element soft relatively to the expanding element that is adapted to be within and is in expanding relation to the expansible element 5 and initially and permanently assembled therewith; and a second expanding element initially, permanently and directly assembled with one of the aforesaid elements and in expanding relation to the expansible element. 10
11. An anchoring device including a tapered expanding element; an expansible element soft relatively to the expanding element that is adapted to be within and is in expanding relation to the expansible element 15 and initially and permanently assembled therewith, this expansible element having a bore tapering similarly to the expanding element and receiving the same; and a second expanding element initially, permanently and directly assembled with one of the aforesaid elements and in expanding relation to the expansible element. 20
12. An anchoring device including a tapered expanding element; an expansible element soft relatively to the expanding element that is adapted to be within and is in expanding relation to the expansible element 25 and initially and permanently assembled therewith, this expansible element having a bore tapering similarly to the expanding element and receiving the same; and a second expanding element initially, permanently and directly assembled with said expansible element and in expanding relation thereto. 30
13. An anchoring device including a tapered expanding element; an expansible element soft relatively to the expanding element that is adapted to be within and is in expanding relation to the expansible element, this 35 and a second expanding element initially, permanently and directly assembled with said expansible element and in expanding relation thereto. 40
14. An anchoring device including a tapered expanding element; an expansible element soft relatively to the expanding element that is adapted to be within and is in expanding relation to the expansible element 45 and initially and permanently assembled therewith, this expansible element having a bore tapering similarly to the expanding element and receiving the same; and a second expanding element initially, permanently and directly assembled with one of the aforesaid elements and in expanding relation to the expansible element. 50
15. An anchoring device including an expanding element; an expansible element soft 55 relatively to the expanding element that is adapted to be within and is in expanding relation to the expansible element; and a second expanding element initially, permanently and directly assembled with said expansible element and in expanding relation to the expansible element. 60
16. An anchoring device including an expanding element; an expansible element soft 65 relatively to the expanding element that is adapted to be within and is in expanding relation to the expansible element; and a second expanding element, said expanding elements having interengaging formations effecting their direct assembly. 70
- In witness whereof, I hereunto subscribe my name this 6th day of December A. D., 1920.
- RALPH S. PEIRCE.
